UNITED STATES PATENT OFFICE.

AARON MARCUS, OF BROOKLYN, NEW YORK, ASSIGNOR TO JOSEPH LEVY AND AARON MARCUS, A PARTNERSHIP DOING BUSINESS AS LEVY AND MARCUS, OF NEW YORK, N. Y.

NECKTIE.

1,212,237.

Specification of Letters Patent. Patented Jan. 16, 1917.

Application filed April 1, 1915. Serial No. 18,527.

To all whom it may concern:

Be it known that I, AARON MARCUS, a citizen of the United States, who resides in Brooklyn, Kings county, and State of New York, whose post-office address is care of Levy & Marcus, 731 Broadway, New York city, have invented a certain new and useful Improvement in Neckties, of which the following is a specification.

10 The object of my invention is to provide a necktie which will be made of three pieces, one at each end cut on a bias and a central intermediate portion of slippery cloth, such as sateen, which will slip easily when being 15 adjusted upon the neck of a wearer and between the parts of a turned down collar.

These and other objects are accomplished by my invention, one embodiment of which is hereinafter set forth.

For a more particular description of my invention, reference is to be had to the accompanying drawings, forming a part hereof, in which—

Figure 1 shows the inside of my improved tie in the back; and Fig. 2 shows the outside of the same, that is, the front. Figs. 3 and 4 are enlarged views, showing where the ends come into contact with the intermediate portion, Fig. 3 showing the front and Fig. 4 the back. Figs. 5, 6 and 7 are sectional views taken on the lines 5—5, 6—6, and 7—7 respectively of Figs. 3 and 4.

Throughout the various views of the drawings, similar reference characters designate similar parts.

My improved tie 1 may be made in many forms. In one, it has a large end 2 and a smaller end 3 which are united by an intermediate portion 4 in a manner which will 40 be described below. The ends 2 and 3 are made of good material cut on a bias and contain all of the tie which shows when worn. The intermediate portion 4 is made of cheaper and smoother material and is 45 preferably not cut on a bias so that it will be strong and will slip easily when the tie is adjusted upon the collar of the wearer, and within the collar of the wearer, when it is a turned-down collar. In addition to 50 the parts 2, 3 and 4, there is a lining 5 which somewhat stiffens and strengthens the tie. These parts 2, 3, 4 and 5 are put together in a manner which will now be described. The ends 2 and 3 are first cut on a bias, as 55 above stated, and then hemmed at their

exposed ends in the conventional manner. They are then laid face down and properly placed with regard to the lining 5 and folded over the same, as indicated in Fig. 1. The connecting portion 4 is then put in place as shown in Fig. 2 and secured in place, so as to secure the ends 2 and 3 and has its intermediate parts with edges overlapping on the front of the tie, as shown in Figs. 2 and 3. The ends 2 and 3, and the intermediate part 4 are held together by suitable stitches 6, which are preferably blind and the lining 5 is held true with regard to the intermediate part 4 by means of suitable rows of stitches 7, as shown. 60 Where the edges of the intermediate portion overlaps between the ends 2 and 3, the overlapping parts are preferably secured by blind stitches 8.

From the foregoing, it is evident that my 75 improved tie is composed of a lining and three parts of exposed cloth, two of which are cut on a bias and are of superior quality, and the connecting part is cut straight and not on a bias, and is preferably made of a slippery cloth, as sateen, so that the tie may be easily adjusted to the collar of the wearer. When the tie is made as above described, it is made of expensive material at the ends 80 and cheaper material in the middle, so that the best possible display may be had at the smallest possible cost. These and other advantage flow from my improved construction, as above set forth.

While I have shown and described one 90 embodiment of my invention, it is obvious that it is not restricted thereto, but is broad enough to cover all structures that come within the scope of the annexed claims.

What I claim is:

1. A necktie having separate ends with edges, an intermediate portion connecting the ends and covering part of their edges at the rear of the tie, with adjacent edges of the intermediate portion secured on the face 95 of the tie.

2. In a necktie, a separate lining, separate ends with edges, and a separate intermediate portion connecting the ends and secured to the lining, the said intermediate portion 100 also having overlapping edges secured together on the face of the tie and also secured over the edges of the ends at the back of the tie.

3. A necktie having a lining, ends cut 110

on a bias and edges on said ends, and an intermediate portion cut straight, the intermediate portion having adjacent edges on the face of the tie and extended so as to cover parts of the edges of the ends at the back of the tie.

4. A necktie having ends with edges, an intermediate portion and a lining, the intermediate portion having overlapping edges 10 on the face of the tie and connected to the

ends by stitching, the intermediate portion being extended so as to cover the edges of the ends at the back of the tie.

Signed at the city, county and State of New York, this 30th day of March, 1915. 15

AARON MARCUS.
